JESSE JAMES TOMPKINS, OF HOUSTON, TEXAS

WOODWORKING MACHINE

Application filed December 5, 1930. Serial No. 500,361.

This invention relates generally to wood-working machines and more particularly to planers, joiners and the like, and has for its primary object to provide, in a manner as hereinafter set forth, a safety device or guard for shielding the cutting or planing element to prevent injury to an operator of the machine.

Another important object of the invention is to provide a woodworking machine of the character described having a safety device or guard which is normally disposed in operative position relative to the cutting means and which is actuated by the work moving toward and over the cutting means to shift the guard to inoperative position in a manner to permit the work to be engaged by the cutting means, the guard returning to its operative position as soon as the operation has been completed and the work has passed the cutting means.

Other objects of the invention are to provide a device of the aforementioned character which will be simple in construction, strong, durable, efficient and reliable in use and which may be manufactured at low cost.

All of the foregoing and still further objects and advantages of the invention may become apparent from a study of the following specification, taken in connection with the accompanying drawings wherein like characters of reference designate corresponding parts throughout the several views, and wherein:

35 Figure 1 is a view showing a guard in accordance with this invention in side elevation mounted in operative position on a joiner, said joiner being partially broken away in vertical longitudinal section.

40 Figure 2 is a view in top plan thereof.

Figure 3 is a fragmentary detail view in vertical cross section taken substantially on the line 3—3 of Figure 1 looking in the direction indicated by the arrows.

45 Figure 4 is a detail view in perspective of one of the actuating levers which are operatively connected to each of a plurality of slidible guard fingers.

50 Figure 5 is a detail view in perspective of one of the slidible guard fingers.

Figure 6 is a detail view in perspective of one of the arcuate, pivoted guards.

Figure 7 is a detail view in perspective showing one of the headed arms 1 each of which is provided for operatively connecting the actuating levers to the slidible guard fingers.

Figure 8 is a fragmentary detail view in perspective showing a portion of the slotted guide and stop plate in which the actuating levers and the connecting arms are operable.

Referring to the drawings in detail, it will be seen that the reference numeral 1 designates an elongated, horizontally disposed table which is provided with a series of spaced, parallel, longitudinally extending slots 2 which are intersected adjacent their forward ends by a transverse opening 3 in which a cutter head 4 is operable, said cutter head being mounted for operation in a housing 5 which is disposed beneath the table 1. Any suitable supporting means may, of course, be provided for the table 1.

A pivot rod 6 extends transversely beneath the table 1 adjacent the rear ends of the slots 2 and mounted for swinging movement in a vertical plane thereon is a series of spaced, parallel levers 7 which have their intermediate portions mounted on the pivot rod 6. The forward end portions of the levers 7 are operable through the slots 2 and said forward end portions terminate adjacent the cutter head 4 and above the vertical plane of said cutter head. The rear end portions of the levers 7 are downwardly offset with respect to the forward end portions thereof and are operable in the slots 8 of a vertically disposed plate 9 which is mounted transversely beneath the table 1.

A horizontally disposed pivot rod 10 is mounted transversely beneath the table 1 adjacent the forward side of the plate 9 and mounted for swinging movement in a vertical plane on the pivot rod 10 is a series of spaced arms 11 which depend from said rod 10 and have their lower end portions pivotally connected to the rear end portions of a series of guard fingers 12 as at 13. Integral heads or extensions 14 extend rearwardly from the upper portions of the arms 11 and

are operable in the slots 8 in the plate 9. An integral lug 15 extends laterally from the free end portion of each of the heads or extensions 14 for engagement by the rear end portions of the levers 7 for operatively connecting said levers and the arms together. As will be apparent, when the forward end portions of the levers 7 are swung downwardly into the slots 2, the rear end portions of the levers will swing upwardly and engage the lugs 15 to swing the arms 11 rearwardly. Springs 16 are mounted on the pivot rod 10 and operatively engaged with the arms 11 for swinging said arms forwardly and thus 10 swinging the levers 7 in the opposite direction through the medium of the lugs 15.

The arms 11 constitute supporting means for the rear ends of the guard fingers 12, as will be apparent. The forward end portions of the guard fingers 12 are slidably supported on an inclined plate or bar 17 which extends transversely beneath the table 1 adjacent the rear side of the transverse opening 3. As clearly illustrated in the drawing, the upper or free end portions of the slidable guard fingers 12 are curved.

Arcuate, pivoted guard fingers 18 are pivotally mounted for swinging movement in a vertical plane as at 19 in the housing 5 beneath the cutter head 4, said pivoted guard fingers extending upwardly forwardly of the cutter head 4 and being operable in the end portions of the slots 2 which are disposed forwardly of the transverse opening 3 in the table 1. As illustrated to advantage in Figure 2 of the drawings, when the slidable guard fingers 12 and the pivoted guard fingers 18 are in operative position above the cutter head 4, the free end portions thereof overlap 20 and it will further be seen that the guard fingers 12 and 18 are disposed in staggered relation to each other. It may be well also to call attention to the fact at this time that the slidable guard fingers 12 project forwardly of the forward ends of the levers 7 and said levers 7 are disposed in the vertical plane of the slidable guard fingers 12. Springs 20 are operatively engaged with the pivoted guard fingers 18 for yieldingly maintaining 30 said pivoted guard fingers in raised or operative position.

Adjacent their pivoted ends, the guard fingers 18 are provided with notches 21 for the reception of the stop rod 22 which is mounted transversely in the housing 5 to limit the swinging movement of the guard fingers 18 under the impulse of the springs 20. In operation, the work is moved forwardly toward the cutter head 4 over the table 1 and engages the forwardly and upwardly inclined forward end portion of the levers 7 which are disposed above the horizontal plane of the table 1. The levers 7 which are thus engaged by said forwardly moving work have their forward end por-

tions swung downwardly and their rear end portions swung upwardly in a manner to swing the arms 11 rearwardly. The arms 11 in turn draw the slidable guard fingers 12 rearwardly on the inclined supporting bar 17, said slidable guard fingers 12 thus being retracted relative to the cutter head 4 and disposed beneath the horizontal plane of the table 1. As the slidable guard fingers 12 approach the limit of their rearward movement the forward end portions of the levers 7 enter the slots 2 as the work passes said forward end portions for engagement by the cutter head 4. The forward end of the work then engages the free ends of the pivoted guard fingers 18 and said guard fingers are swung downwardly through the forward portions of the slots 2 into the housing 5 in a manner to permit the work to pass.

When the rear end of the work passes the free ends of the slidable guard fingers 12 the springs 16 which are operatively engaged with the arms 11 swing said arms 11 forwardly and return the slidable guard fingers 12 to raised or operative position above the cutter head 4. The lugs 15 engage the rear end portions of the levers 7 and return said levers 7 to raised or operative position. If desired, the rear end portions of the levers 7 may be heavier than the forward end portions for overbalancing said forward end portions and permit the levers 7 to be returned by gravity to operative position as soon as the rear end of the work has passed the forward ends of the levers. When the rear end of the work has passed the forward ends of the slots 2 and thus freed the pivoted guard fingers 18, said guard fingers 18 are returned to raised or operative position by the springs 20. Only the guard fingers which are engaged by the forwardly moving work will be moved to inoperative position to permit the passage of the work and the engagement of said work with the cutter head 4. The remaining guard fingers will thus remain in operative position on one or both sides of the work to protect the operator of the machine from injury by the cutter head. The slotted plate 9 constitutes means for limiting the swinging movement of the levers 7 in one direction and in addition constitutes a guide for retaining the levers 7 against lateral movement. Of course, any desired number of the guard fingers and the actuating levers therefor may be provided and said fingers and levers may be spaced as desired on the table 1.

It is believed that the many advantages of a device in accordance with this invention will be readily understood and although the preferred embodiments of the invention is as illustrated and described, it is to be understood that changes in the details of construction, may be had which will fall within the scope of the invention as claimed.

Having thus described my invention, what I claim as new is:

1. A woodworking machine of the character described comprising, in combination, a table having a longitudinal slot therein and further having a transverse opening communicating with the slot, a rotary cutter operable in the opening, a lever pivoted intermediate its ends, one end portion of the lever being operable through the slot for engagement and actuation by the work on the table, the other end portion of the lever extending beneath the table, an arm pivotally mounted for swinging movement beneath the table, means operatively connecting the arm to the rear end portion of the lever for engagement by said lever upon swinging movement of the lever in one direction, a spring operatively engaged with the arm for moving said arm in the opposite direction, a guard finger pivotally connected to the arm for actuation by said arm and having one end portion operable through the slot for disposition above the cutter, and a bar mounted transversely beneath the table for slidably supporting said one end portion of the guard fingers, said means for operatively connecting the arm to the lever comprising an integral head on the arm, and a lug mounted on the head and disposed in the path of travel of the lever for engagement by said lever.
2. A woodworking machine of the character described comprising, in combination, a table having a longitudinal slot therein and further having a transverse opening communicating with the slot, a rotary cutter operable in the opening, a lever pivoted intermediate its ends, one end portion of the lever being operable through the slot for engagement and actuation by the work on the table, the other end portion of the lever extending beneath the table, an arm pivotally mounted for swinging movement beneath the table, means operatively connecting the arm to the rear end portion of the lever for engagement by said lever upon swinging movement of the lever in one direction, a spring operatively engaged with the arm for moving said arm in the opposite direction, a guard finger pivotally connected to the arm for actuation by said arm and having one end portion operable through the slot for disposition above the cutter, and a bar mounted transversely beneath the table for slidably supporting said one end portion of the guard fingers, said means for operatively connecting the arm to the lever comprising an integral head on the arm, and a lug mounted on the head and disposed in the path of travel of the lever for engagement by said lever.
3. A woodworking machine of the character described comprising, in combination, a work supporting table having a longitudinal slot therein and further having a transverse opening intersecting the slot in spaced relation to the ends of the slot, a rotary cutter operable in the opening, a vertically disposed plate having a vertical slot therein mounted beneath the table in spaced relation to one end of the first named slot, a lever pivoted intermediate its ends for swinging movement in a vertical plane and having one end portion operable through the first named slot for disposition above the table for engagement and actuation by the work, the other end portion of the lever extending beneath the table and operable in the slot in the plate, an arm pivotally mounted for swinging movement in a vertical plane beneath the table, a head formed integrally on the arm and operable in the slot in the plate, a lug formed integrally on the head and extending laterally therefrom and disposed in the path of travel of said other end portion of the lever for engagement thereby in a manner to operatively connect the arm to the lever for actuation by said lever upon movement of the lever in one direction, an inclined bar mounted transversely beneath the table adjacent the cutter, a guard finger having one end operatively connected to the arm and its other end portion slidably supported on the bar, said other end portion of the guard finger being operable through the first named slots for disposition above the cutter, resilient means operatively connected with the arm for yielding urging said arm in the other direction.
4. A woodworking machine of the character described comprising, in combination, a work supporting table having a longitudinal slot therein and further having a transverse opening intersecting the slot in spaced relation to the ends of the slot, a rotary cutter operable in the opening, a vertically disposed plate having a vertical slot therein mounted beneath the table in spaced relation to one end of the first named slot, a lever pivoted intermediate its ends for swinging movement in a vertical plane and having one end portion operable through the first named slot for disposition above the table for engagement and actuation by the work, the other end portion of the lever extending beneath the table and operable in the slot in the plate, an arm pivotally mounted for swinging movement in a vertical plane beneath the table, a head formed integrally on the arm and operable in the slot in the plate, a lug formed integrally on the head and extending laterally therefrom and disposed in the path of travel of said other end portion of the lever for engagement thereby in a manner to operatively connect the arm to the lever for actuation by said lever upon movement of the lever in one direction.

actuation by said lever upon movement of the lever in one direction, an inclined bar mounted transversely beneath the table adjacent the cutter, a guard finger having one end operatively connected to the arm and its other end portion slidably supported on the bar, said other end portion of the guard finger being operable through the first named slots for disposition above the cutter, resilient means operatively connected with the arm for yieldingly urging said arm in the other direction, an arcuate guard finger pivotally mounted beneath the table and having one end portion operable in the slot for disposition above the cutter, and resilient means operatively engaged with the arcuate guard finger for yieldingly urging same toward its operative position.

5. A woodworking machine of the character described comprising, in combination, a work supporting table having a longitudinal slot therein and further having a transverse opening intersecting the slot in spaced relation to the ends of the slot, a rotary cutter operable in the opening, a vertically disposed plate having a vertical slot therein mounted beneath the table in spaced relation to one end of the first named slot, a lever pivoted intermediate its ends for swinging movement in a vertical plane and having one end portion operable through the first named slot for disposition above the table for engagement and actuation by the work, the other end portion of the lever extending beneath the table and operable in the slot in the plate, an arm pivotally mounted for swinging movement in a vertical plane beneath the table, a head formed integrally on the arm and operable in the slot in the plate, a lug formed integrally on the head and extending laterally therefrom and disposed in the path of travel of said other end portion of the lever for engagement thereby in a manner to operatively connect the arm to the lever for actuation by said lever upon movement of the lever in one direction, an inclined bar mounted transversely beneath the table adjacent the cutter, a guard finger having one end operatively connected to the arm and its other end portion slidably supported on the bar, said other end portion of the guard finger being operable through the first named slots for disposition above the cutter, resilient means operatively connected with the arm for yieldingly urging said arm in the other direction, an arcuate guard finger pivotally mounted beneath the table and having one end portion operable in the slot for disposition above the cutter, and resilient means operatively engaged with the arcuate guard finger for yieldingly urging same toward its operative position, and a stop rod disposed beneath the table for engagement with the

65 arcuate finger for limiting the swinging

movement of said arcuate finger under the impulse of the last named resilient means.

6. A woodworking machine of the character described comprising, in combination, an elongated table having a series of spaced, parallel longitudinally extending slots therein and further having a transverse opening intersecting the slots, in spaced relation to the ends of said slots, a rotary cutter operable in the opening, a pair of pivot rods mounted transversely in spaced relation to each other beneath the table, a plurality of levers pivotally mounted intermediate their ends on one of the pivot rods, one end portion of the levers being operable through one end portion of the slots for disposition above the table for engagement and actuation by the work on the table, the other end portions of the levers extending beneath the table, a plurality of arms pivotally mounted for swinging movement on the other of the pivot rods, integral heads on the one end portion of the arms, integral lugs extending laterally from the heads for engagement by said other end portions of the levers for operatively connecting the arms to the levers for actuation by said levers upon swinging movement of the levers in one direction, a transverse slotted plate mounted vertically beneath the table, the levers and the heads being operable in the slots in the plates, an inclined bar mounted transversely beneath the table adjacent the cutter, a plurality of guard fingers having one end pivotally connected to the arms and their other end portions slidably mounted on the inclined bar and operable through the slots for disposition above the cutter, and a plurality of arcuate guard fingers pivotally mounted beneath the table and operable through the other end portions of the slots for disposition above the cutter.

7. A woodworking machine of the character described comprising, in combination, an elongated table having a series of spaced, parallel longitudinally extending slots therein and further having a transverse opening intersecting the slots, in spaced relation to the ends of said slots, a rotary cutter operable in the opening, a pair of pivot rods mounted transversely in spaced relation to each other beneath the table, a plurality of levers pivotally mounted intermediate their ends on one of the pivot rods, one end portion of the levers being operable through one end portion of the slots for disposition above the table, the other end portions of the levers extending beneath the table, a plurality of arms pivotally mounted for swinging movement on the other of the pivot rods, integral heads on the one end portion of the arms, integral lugs extending laterally from the heads for engagement by said other end portions of the levers for operatively connecting the arms to the levers for actuation by said levers upon swinging movement of the levers

in one direction, a transverse slotted plate mounted vertically beneath the table, the levers and the heads being operable in the slots in the plates, an inclined bar mounted transversely beneath the table adjacent the cutter, a plurality of guard fingers having one end pivotally connected to the arms and their other end portions slidably mounted on the inclined bar and operable through the slots for disposition above the cutter, and a plurality of arcuate guard fingers pivotally mounted beneath the table and operable through the other end portions of the slots for disposition above the cutter, springs mounted on said other pivot rod and operatively engaged with the arms for swinging said arms in one direction in a manner to shift the first named guard fingers to operative position, springs operatively engaged with the second named guard fingers for yieldingly urging said second named guard fingers toward their operative position, and a rod mounted transversely beneath the table for engagement with the second named guard fingers for limiting the swinging movement thereof under the impulse of the last named springs.

In testimony whereof I affix my signature.
JESSE JAMES TOMPKINS.
